US00D966790S

(12) **United States Design Patent** (10) Patent No.: **US D966,790 S**
 Xia et al. (45) Date of Patent: **** Oct. 18, 2022**

(54) **DRINKING BOTTLE LID**

(71) Applicant: **ZHEJIANG FEIJIAN TECHNOLOGY CO., LTD.**, Jinhua (CN)

(72) Inventors: **Feijian Xia**, Yongkang (CN); **Chenhan Ouyang**, Anqing (CN)

(73) Assignee: **ZHEJIANG FEIJIAN TECHNOLOGY CO., LTD.**, Jinhua (CN)

(**) Term: **15 Years**

(21) Appl. No.: **29/773,471**

(22) Filed: **Mar. 9, 2021**

(51) LOC (13) Cl. **07-01**

(52) U.S. Cl.

USPC **D7/392.1; D9/449**

(57) **CLAIM**

The ornamental design for a drinking bottle lid, as shown and described.

DESCRIPTION

FIG. 1 is a top perspective view of a drinking bottle lid showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the drinking bottle lid that form no part of the claimed design.

1 Claim, 8 Drawing Sheets
